UNITED STATES PATENT OFFICE.

CHARLES ANDREW MCCLAIR, OF NORTH BROOKFIELD, CANADA, ASSIGNOR
OF TWO-THIRDS TO JOHN MCGUIRE, OF SAME PLACE, AND GARDNER
CLISH, DUNCAN MCDONALD, AND SILAS R. TUPPER, OF TRURO, CANADA.

STAMP-TAPPET.

SPECIFICATION forming part of Letters Patent No. 599,400, dated February 22, 1898.

Application filed December 24, 1896. Serial No. 616,959. (No model.)

To all whom it may concern:

Be it known that I, CHARLES ANDREW MCCLAIR, a British subject, residing at North Brookfield, in the county of Queens, in the Province of Nova Scotia, Dominion of Canada, have invented a new and useful Improvement in Stamp-Tappets, of which the following is a specification.

My invention relates to the cylindrical-shaped pieces of cast-iron, commonly called "tappets," which are secured to the stems of ore-crusher stamps and through which a vertical reciprocating motion is imparted to the stamps by the action of cams engaging with and disengaging from said tappets; and the object of my invention is to increase the durability of said cams by preserving a smooth, even, and comparatively soft wearing-surface on the tappet; also, to do away with the use of a lubricator on the cams, which is objectionable in gold-mills, and, further, to decrease the noise caused when the iron surfaces of cams and tappets come in contact. I attain these objects by the device illustrated in the accompanying drawings, in which—

Figure 1 is a vertical section of a stamp-tappet which embodies my invention complete. Fig. 2 is a vertical section of my attachment to the stamp-tappet alone. Fig. 3 is a plan view of the same.

Similar letters and numerals refer to similar parts throughout the several views.

In the drawings, A is the neck of the tappet. B is the key-boss.

35 F is the face.

C is the bore through which the stamp-stem passes, onto which stem the tappet is secured by the keys o o, which keys, pressing against the gib f, draw the tappet firmly against and 40 onto the stem.

d d are two metal bands shrunk on or otherwise secured to the heads c c of the tappet and which project beyond the faces F F.

e e are metal rings about one-eighth of an inch thick, which are cast or otherwise formed or secured in the recesses i, formed in the tappet-heads, and which project beyond the faces F F the same distance as do the bands d d. These rings are preferably made having the internal diameter about one-eighth of an inch 45 larger than the stem, so as to allow of a clearance between them. 50

1 2 3 4 5 6 7 8 are pieces of hard wood boiled in oil, set on end, and pressed in place tightly, completely filling the space at each end of 55 the tappet between the band d, the ring e, and the face F.

The cams by which the stamps are raised engaging with the wood-filled tappets, the noise which is connected with the use of iron 60 tappets is largely reduced, the necessity for constant lubrication is removed, the life of a cam is greatly increased, and the necessity for chilled or hardened wearing parts is also done away with. 65

I do not claim that wood filling is essential, as any equivalent may be used. Neither do I claim that the bands and the rings d d and e e made separate from the tappet are essential; but 70

What I do claim as new, and desire to secure by Letters Patent, is—

A stamp-tappet consisting of the neck, having recesses i, formed in each of its ends, and shoulders formed upon its outer edges, combined with the rings d, e, applied to each end of the neck, and the filling-blocks of wood inserted between the rings, and forming bearing-surfaces for the tappet, substantially as shown. 75
